UNITED STATES PATENT OFFICE.

CHARLES E. MICHAELS, OF WILSON, PENNSYLVANIA.

NOZZLE FOR LADLES.

1,072,972.

Specification of Letters Patent.

Patented Sept. 9, 1913.

Application filed July 24, 1913. Serial No. 781,026.

To all whom it may concern:

Be it known that I, CHARLES E. MICHAELS, a citizen of the United States, residing at Wilson, in the county of Allegheny and 5 State of Pennsylvania, have invented certain new and useful Improvements in Nozzles for Ladles; and I do declare the following to be a full, clear, and exact description of the invention, such as will enable 10 others skilled in the art to which it appertains to make and use the same.

This invention relates to metal founding, and more especially to ladles having an internal stopper; and the object of the same 15 is to produce an improved nozzle for ladles of this kind, with improved means for supporting it in the outlet opening of the ladle in such way that a cracked, burned-out, or leaky nozzle may be replaced by a new one 20 with a few minutes' work and without the use of special tools or the employment of fire-clay which must be carefully packed and then burned before the ladle can again be put into service. This and other objects are carried out by constructing the device in the manner hereinafter more fully described and claimed, and as shown in the drawings wherein—

Figure 1 is a section through the bottom 30 of the ladle showing this improved nozzle in place; Fig. 2 is an enlarged section through the nozzle and that portion of the ladle immediately surrounding the same; Fig. 3 is a cross section on the line 3—3 of Fig. 2; Fig. 35 4 is a section similar to Fig. 2 excepting that in this case the retaining plate has not yet been applied and the nozzle is in the act of being put into place. Fig. 5 is a cross section on the line 5—5 of Fig. 4; Fig. 6 is 40 a vertical section similar to Fig. 4 excepting that the nozzle has been inserted as far as possible and is here shown as held in place by a retainer described below; Figs. 7 and 8 are side elevations of the nozzle removed, these views showing it in two different positions; and Fig. 9 is a cross section on the line 9—9 of Fig. 7; Fig. 10 is a detail of the retaining plate.

In the drawings the letter L designates a 50 ladle such as is ordinarily employed for pouring molten metal, the same having a steel shell S lined on its interior with fire brick B, and the letter O designates an outlet opening through the brick and the shell at a proper point. In the use of ladles of this kind, such openings are closed by a

tubular nozzle whose bore is plugged from within the ladle, and from time to time the plug is lifted or removed by mechanism forming no part of the present invention, so that a portion of the molten metal runs out through the nozzle and is used. The intense heat of the metal in time burns the nozzle so that the same becomes cracked, broken, and even perhaps pulverized, with the result 65 that it is no longer useful for retaining the molten metal which latter leaks out of the opening and around or through the nozzle beneath the plug. Assuming, however, that the ladle is of sufficient size and the pouring-off occurs so frequently and in such ample 70 charges that the nozzle may be used until the ladle is emptied; it then becomes desirable to replace the nozzle before the ladle is filled again. Ordinarily this operation 75 involves considerable time and the services of two or three workmen, and meanwhile of course the ladle is out of use and the total loss to the founder is considerable. The object of the present invention is to produce 80 a nozzle which can be inserted in the outlet opening and packed very quickly, so that this loss to the founder will be saved to a considerable extent.

Coming now to the details of the present 85 invention, I prefer to form a recess 1 within the inner face of the fire brick B around the outlet opening O, and insert into said recess a magnesite block 2 having a dished upper face 3 converging from all sides of 90 the block downward to a central opening 4 which is somewhat smaller than the outlet opening O in the ladle wall. The shape of the opening 4 through the block may be such as is desired, whereas the shape of the outlet opening O through the ladle-wall is round 95 as best seen in Fig. 5, and in carrying out my invention it is essential that the outlet opening O be larger than the outlet opening 4 as will be seen. This block may be held 100 in position within the fire brick B by any suitable means, although additional elements or means for this purpose are hardly necessary as the intense heat will soon cause the block to adhere to the brick. One further reason why I prefer to employ this 105 block is in order that the outlet opening 4 through it may be well defined and that the opening O through the fire brick may be somewhat protected from extreme heat. Through the shell S directly beneath said opening O I form a square opening 5 con-

centric with the other openings above referred to, and the longest diameter of this opening is equal to any diameter of the round opening O as seen in Fig. 3, with the result that four segmental shoulders 6 are produced on the inner face of the shell around the opening 5 and within the opening O. I have spoken of the latter as an "opening" although it is in effect a passage 10 for it has a length equal nearly to the thickness of the fire brick, and this is a matter of importance in the present case. Secured to the shell around the opening 5 are fastening devices 7, herein shown as bolts whose 15 headed ends stand uppermost and whose threaded ends are at the bottom and adapted to receive nuts 8 which support a retainer, herein shown in the shape of a plate 9 having through it a round hole 10 concentric with the holes above described, and 20 whose diameter is equal to the shortest diameter of the square opening 5.

The nozzle proper is best illustrated in Figs. 7 and 8, and is molded or formed as usual from fire clay or fire brick or any suitable vitreous material. Its upper portion is square as at 12, beneath which it is shouldered as at 13 and its lower portion is rounded as at 14. Throughout its length it 25 has a bore 15, preferably enlarged or flared at its upper end as at 16 into what might be called a "mouth" whose inlet end is by preference of the same size and shape as the opening 4 through the block 2. Passing 30 through the latter and seating on the mouth 16 is the plug, indicated by the letter P in Fig. 1, although this forms no part of the present invention. When the same is in place it checks the outlet of molten metal 35 through the block 2 and the bore of the nozzle, but when the plug is raised the metal can flow in a manner well known to those familiar with this art.

With the parts as thus constructed, the 40 insertion of a nozzle is effected as follows: The retainer 9 having been removed and the old and worn-out nozzle dug out and extracted, along with the packing which surrounds it, the entire ladle is by preference turned 45 on its trunnions (not shown in the drawings) so that the outlet opening or passage O stands horizontal or substantially so, it being understood that at this time the plug P is withdrawn and the ladle is empty. A 50 new nozzle is now passed upward, or rather horizontally inward, by inserting its squared end 12 through the square hole 5 in the shell S as seen in Fig. 4, and the nozzle is then borne inward until the inner extremity 55 strikes against the block 2. Then it is given a one-eighth revolution within the opening O which, as above stated, has a diameter equal to the longest diameter of said squared portion and therefore such revolution is permitted. This brings the corners of the

shoulders 13 behind the shoulders 6 formed around the square hole 5 in the shell S, so that the parts stand as seen in Fig. 2, and yet the square opening 5 through the shell S is not closed by the round portion 14 of the nozzle, as will be clear by an inspection of Figs. 3 and 5. At this point I preferably make use of a supporting device best seen in Fig. 6. This comprises an eye-bolt 20 whose stem passes through the block 2 and the 70 nozzle, whose eye 21 is at its upper or inner end and elongated laterally to such an extent that it reaches across the opening 4 as shown, and whose lower threaded end 22 retains a hand nut 23 which in turn supports 80 a washer 24 that rests against the lower (outer) end of the nozzle. When this nut is turned up tight the nozzle is pressed home so that its upper end is forced into close contact with the block 2, and the step next to be described may now take place. I might here say that eventually the nut 23 and washer 24 are detached, and a hook H is let 85 down into the ladle L as indicated in Fig. 6 whereby this entire device can be withdrawn. I prefer the use of this supporting device, although it is not absolutely necessary with my invention, as it is quite possible to insert the nozzle and pack it as next to be described without the use of such a device at 90 all. However, as above stated, this invention is designed to save time, and the insertion and removal of such a device occupy but a few moments and its use results in the proper application of the nozzle under 95 all circumstances so that it rarely if ever occurs that any leak will follow. By this I mean that a nozzle made of fire clay or other vitreous material while theoretically of the proper proportions, may sometimes 100 be a little short so that when its shoulder 13 rests on the shoulder 6 of the shell S the upper end does not always contact closely with the lower face of the block 2; and if it were not possible to quickly chip off a portion of the shoulder 13 so as to make it fit within the passage O, a nozzle which was 105 too long could not be used. Furthermore this supporting device performs the function of holding the nozzle strictly centered 110 throughout the length of the opening O and with its mouth 16 registering with the opening 4 through the block 2, and for these various reasons I prefer to use the device.

The next step in the operation is to pack 115 the space within and throughout the length of the opening O and around the squared portion 12 of the nozzle, and this may be done with my invention by the use of sand or any pulverulent material, although the 120 same need not be moistened at all and therefore does not require the subsequent use of gas or any other blaze to set it in position. Attention is directed to the fact that this 125 is an important feature of my invention and 130

saves both time and expense. The packing is indicated by the numeral 25, and, on the assumption that it is sand, it is passed through the corners of the square opening 5 in the shell S and assumes the position shown in Figs. 3 and 6. After the packing 25 has been put into place, the plate 9 is applied and the nuts 8 engaged with the bolts 7 (if nuts and bolts be employed for holding 10 said plate in place) and the packing is thereby absolutely prevented from becoming lost out. The nut 23 and washer 24 are then removed as above suggested, and a hook H passed in so that the fastening device can 15 be wholly withdrawn. The ladle L is then righted, a plug P let down into the opening 4 and the mouth 16 of the bore of the nozzle, and the ladle is ready for renewed use.

Experience has shown that I can remove a 20 useless nozzle and replace it by a new one thoroughly packed so that there will be no leak of the molten material in from ten to fifteen minutes, and the entire work can be done by one man. By the present method it 25 requires the services of two men, and the exchange cannot be effected in less than one-half an hour. I do not wish to be confined strictly to the details of construction above set forth, and the materials and proportions 30 of parts are obviously not essential to the successful operation of this invention.

What is claimed as new is:

1. A ladle comprising a shell with a fire-brick lining, the latter having through it a 35 round outlet opening and the shell having through it a square opening concentric with that in the lining and whose longest diameter equals the diameter of said round opening; combined with a nozzle having a 40 squared upper portion adapted to be passed through said square opening and a round lower portion whose diameter corresponds with the smallest diameter of said square opening.

45 2. A ladle comprising a shell with a fire-brick lining, the latter having through it a round outlet opening and the shell having through it a square opening concentric with that in the lining and whose longest 50 diameter equals the diameter of said round opening; combined with a block over the inner end of the opening through said brick and having through it an opening concentric therewith but smaller, and a nozzle having 55 a squared upper portion of a size to pass through the square opening in the shell and of a length corresponding with the distance between said shell and block, and a round lower portion whose diameter equals the 60 smallest diameter of the opening through the shell.

3. A ladle comprising a shell with a fire-brick lining, the latter having through it a round outlet opening and the shell having 65 through it a square opening concentric with

that in the lining and whose longest diameter equals the diameter of said round opening; combined with a block over the inner end of the opening through said brick and having through it an opening concentric 70 therewith but smaller, and a nozzle having a squared upper portion of a size to pass through said square opening in the shell and of a length equal to the distance between the contiguous faces of said block 75 and shell, and a reduced lower portion projecting through said shell when the square portion is in place.

4. A ladle comprising a shell with a fire-brick lining, the latter having through it a round outlet opening and the shell having through it a square opening concentric with that in the lining and whose longest diameter equals the diameter of said round opening; combined with a block over the inner 80 end of the opening through said brick and having through it an opening concentric therewith but smaller, the upper face of the block converging from its periphery to the edges of its opening, and a nozzle having a 85 squared upper portion of a size to pass through said square opening in the shell and of a length equal to the distance between the contiguous faces of said block and shell, the nozzle having a bore throughout its length 90 enlarged at its upper end to a size corresponding with that of the opening through 95 said block.

5. The combination with a ladle having a round outlet opening through its wall recessed at its inner end, a block seated in said recess and having through it an opening concentric with but smaller than that in said wall, and a shell surrounding said wall and having through it an opening concentric with but smaller than that through said wall; of a nozzle whose upper end is of a size and shape to be passed through the opening in the shell and to be turned within the opening in said wall when its inner end 100 contacts with the block, and means for holding said nozzle in place while it is being packed.

6. The combination with a ladle having a round outlet opening through its wall recessed at its inner end, a block seated in said recess and having through it an opening concentric with but smaller than that in said wall, and a shell surrounding said wall and having through it an opening concentric 115 with but smaller than that through said wall; of a nozzle whose upper end is of a size and shape to be passed through the opening in the shell and to be turned within the opening in said wall when its inner end 120 contacts with the block; a retaining device consisting of an eye-bolt whose shank passes through the bore of the nozzle and whose head is enlarged laterally so as to span the opening through said block, and 125 130

a washer and nut applied to the lower end of said bolt against the outer end of the nozzle.

7. The combination with a ladle having an outlet passage through its wall which is round throughout most of its length, reduced and rounded at its inner end, and reduced and angular at its outer end; of a nozzle having an angular head adapted to pass through the angular opening in the outer end of said passage and to be rotated within the round portion thereof.

8. The combination with a ladle having an outlet passage through its wall which is round throughout most of its length, reduced and round at its inner end, and reduced and angular at its outer end; of a

nozzle having an angular head adapted to pass through the angular opening in the outer end of said passage and to be rotated within the round portion thereof, and a reduced and round lower end adapted to project through said angular opening when said head is in place, and a retaining plate detachably secured to the outer face of said wall and having an opening closely surrounding the protruding end of the nozzle.

In testimony whereof I have hereunto set my hand in presence of two subscribing witnesses.
